PROCESS FOR MAKING BOWLING PINS

Ralph C. Clark, Ventura, and Ray E. Clark,
Willowbrook, Calif.

Application October 8, 1946, Serial No. 702,046

4 Claims. (Cl. 18—59)

1 Our invention relates to a new and improved process for making bowling pins.

It is well known that bowling pins made entirely of wood are subject to hard wear and due to the impact of bowling balls and hard wood bowling alleys. The pins become nicked and gouged, especially at and around their bottom standing surface, thus making it difficult and often impossible to stand such worn pins upright on the alley surface. Worn pins also become unbalanced due to such wear and are therefore obnoxious and undesirable to professional as well as amateur bowlers.

In view of the foregoing we have developed a new and improved process for making bowling pins having a rubber base or bottom.

A complete understanding of our process will be had from the following detailed description and claims of the same taken in conjunction with the annexed drawings where like parts are indicated by like reference characters and where-in:

Figure 1 is a side elevation partly in section of a typical bowling pin showing the necessary undercutting of the pin base prior to the insertion of the rubber.

Figure 2 is a bottom plan view showing a wooden bowling pin incomplete in form and showing the concaved bottom having a centrally disposed hollow opening with a plurality of openings extending radially therefrom.

Figure 3 is a vertical section of a heating mold showing the aforementioned incomplete bowling pin have the bottom opening filled with uncured rubber and being heated.

Figure 4 indicates in vertical section a mold of the shape of a given bowling pin and containing the desired amount of rubber to be molded to the wooden pin in order to form its base.

Figure 5 shows the wooden bowling pin in the mold and the said rubber bottom being molded to the same by means of temperature and pressure.

Figure 6 is a side elevation partly in section of a bowling pin having a rubber base formed by means of our new process hereinafter described.

In manufacturing a bowling pin with a rubber base it is important that a type of rubber composition be selected so as to impart to the completed product the properties found in the conventional all wooden pin. Such properties are weight, balance, and elasticity.

In our improved process a conventional type wooden bowling pin is formed minus the amount of base section desired to be formed of rubber; said incomplete wooden pin is then provided with

2 a concaved bottom surface having a centrally disposed or located hollow opening with a plurality of grooves extending radially therefrom. In Figures 1 and 2 reference character 1 indicates the main body of the pin, 2 indicates the centrally disposed bottom hole, and 3 the radial grooves as to hole 2.

The main body of the wooden bowling pin having been prepared as above indicated raw or non-cured rubber of desirable composition to give the desired properties is cut from desirable stock so as to fill and completely pack the said bottom openings 2 and 3. Said bottom section of the pin containing the inserted non-cured rubber is then preheated in a suitable container or mold to a temperature ranging from 200 degrees Fahrenheit to 350 degrees Fahrenheit, in order that the inserted rubber may become soft, pliable, or plastic. Said temperature depends upon the composition of the rubber to be used as the pin base. This is called the pre-heating operation.

Figure 3 indicates the pre-heating operation and reference character 4 indicates the rubber in the radial grooves 3, 5 indicates the rubber in the bottom central hole 2 and 6 any desirable mold for pre-heating.

A forming mold 7 is prepared and so designed as to form the desired shape of the pin bottom, and in this mold 7 is placed a predetermined amount of non-cured rubber 8, this amount being equal to the amount necessary to form the base of a completed bowling pin. The predetermined amount of rubber 8 contained in the forming mold 7 indicated in Figure 4 is heated to a temperature between 100 and 350 degrees Fahrenheit until the mass is molten and plastic. The exact temperature required depends upon the composition of rubber being used. The incomplete pin after being preheated and containing inserted rubber 4 and 5 in a pliable state is then placed in the forming mold 7 containing the rubber 8 to form the pin base as indicated in Figure 5. The temperature is raised, depending on the composition of the rubber used, in order to have all the rubber in a molten state and to facilitate vulcanization of the two bodies of rubber, namely that contained in the pin base and that contained in the forming mold 7. The pin 1 is then placed under increased pressure by any suitable means, and the temperature increased to the vulcanizing temperature. Under these conditions of temperature and pressure the rubber is allowed to cure for a length of time depending upon the composition of the rubber.

When said rubber is cured the temperature and pressure are reduced, and the bowling pin removed from the forming mold. The resultant assembly is a completely formed bowling pin having a rubber base, as indicated in Figure 6 of the accompanying drawings.

We have used a rubber composition to form a rubber base bowling pin, said rubber requiring a pre-heat temperature of 270 to 280 degrees Fahrenheit, a curing or vulcanizing temperature of 290 to 300 degrees Fahrenheit, and a curing pressure of 500 pounds per square inch. Our resultant product is a very durable, serviceable, and practical bowling pin of an improved type.

It is imperative that a proper rubber composition be selected, of a type capable of being molded to wood, that does not mark or deface the bowling alley floor, that responds to impact substantially as does wood, and in its molded form must weigh substantially that of wood per unit volume.

What we claim as our invention is:

1. In a process of making a wooden bowling pin having a rubber base, the steps comprising forming said pin with a concave bottom having a plurality of radial grooves, inserting non-cured rubber in said bottom end grooves, pre-heating said bottom to a temperature sufficient to convert the thus inserted rubber to a pliable state, forming a separate body of non-cured rubber in amount sufficient to form the base of said pin, placing said pre-heated bottom upon said molten body, and subjecting the thus-assembled bottom and molten body to an elevated temperature and pressure to form a cured rubber base attached to said concave bottom of the pin.

2. In a process of making a wooden bowling pin having a rubber base, the steps comprising forming said pin with an under-cut bottom having a centrally-disposed hollow opening and a plurality of radial grooves extending therefrom, inserting non-cured rubber in said opening and grooves, pre-heating said bottom to a temperature sufficient to convert the thus inserted rubber to a pliable state, forming a separate molten body of non-cured rubber in amount sufficient to form the base of said pin, placing said pre-heated bottom upon said molten body, and subjecting the thus-assembled bottom and molten body to an elevated temperature and pressure to form a cured rubber base attached to said under-cut bottom of the pin.

3. In a process of making a wooden bowling pin

having a rubber base, the steps comprising forming said pin with an under-cut bottom having a centrally-disposed hollow opening and a plurality of radial grooves extending therefrom, inserting non-cured rubber in said opening and grooves, pre-heating the said bottom to a temperature ranging from 200-degrees to 350-degrees Fahrenheit to convert the thus-inserted rubber to a pliable state, forming a separate molten body of non-cured rubber in amount sufficient to form the base of said pin, placing said pre-heated bottom upon said molten body, and subjecting the thus-assembled bottom and molten body to a temperature ranging from 200-degrees to 350-degrees Fahrenheit and a pressure of 500-pounds per square inch to form a cured rubber base attached to said under-cut bottom of the pin.

4. In a process of making a wooden bowling pin having a rubber base, the steps comprising forming said pin with an under-cut bottom having a centrally-disposed hollow opening and a plurality of radial grooves extending therefrom, inserting non-cured rubber in said opening and grooves, pre-heating the said bottom to a temperature ranging from 270-degrees to 280-degrees Fahrenheit to convert the thus-inserted rubber to a pliable state, forming a separate molten body of non-cured rubber in amount sufficient to form the base of said pin, placing said pre-heated bottom upon said molten body, and subjecting the thus-assembled bottom and molten body to a temperature ranging from 290-degrees to 300-degrees Fahrenheit and a pressure of 500-pounds per square inch to form a cured rubber base attached to said under-cut bottom of the pin.
